[57] CLAIM

The ornamental design for a combined storage and retrieval unit for TV and VCR remote controls, as shown and described.

DESCRIPTION

FIG. 1 is a perspective view showing my new design for a combined storage and retrieval unit for TV and VCR remote controls;

FIG. 2 is a front elevational view thereof;

FIG. 3 is a top plan view thereof;

FIG. 4 is a left elevational view thereof, the right side elevational view being a mirror image;

FIG. 5 is a rear elevational view thereof; and,

FIG. 6 is a bottom plan view thereof.

FIG. 4.

FIG. 5.

FIG. 6.
